PNEUMATIC MOTOR FOR UNIT VENTILATORS

Robert P. Roetter, Gary, Ind., assignor to Minneapolis-Honeywell Regulator Company, Minneapolis, Minn., a corporation of Delaware

Application October 27, 1949, Serial No. 123,851

14 Claims. (Cl. 137—790)

1

The present invention relates to a pneumatic motor especially adapted for unit ventilators.

The most widely used control sequence for unit ventilators uses a cycle wherein the motor, on a rise in branch line pressure, first operates the fresh air damper to a predetermined minimum position and then, on a further rise in branch line pressure, "hesitates" or remains inoperative, and finally, upon a still further rise in branch line pressure, the dampers are gradually operated to a wide-open position. This function has been obtained in the past by "picking up" a second spring by the connecting linkage at the beginning of the hesitation part of the cycle which is preloaded to require a predetermined branch pressure to overcome it and thus start the third phase of the cycle. This arrangement has the disadvantage that a different pickup spring is needed for every different installation, for its characteristics not only affect the hesitation part of the cycle but also determine the third or finishing part of the cycle. The present motor, by using three springs, can be readily adjusted for any installation without substituting any springs, hence it is a major object of the present invention to provide an improved pneumatic motor for unit ventilators.

It is a further object to provide a pneumatic motor for unit ventilators that is more compact than previous motors and that needs no exterior or supplemental springs to obtain a desired sequence of operation.

It is also an object to provide a pneumatic motor having an improved preloaded spring construction that is easily manufactured and very compact.

It is another object to provide a pneumatic motor that is easily adjusted to operate to a predetermined end position at a predetermined air pressure.

It is a still further object to provide a pneumatic motor for unit ventilators wherein a hesitation cycle may be used or not depending upon the adjustment of the motor.

These and other objects will become apparent upon a study of the following specification and drawings wherein:

Figure 1 is an elevation view of the present motor with parts in section and parts broken away.

Figure 2 is a similar view taken at right angles to Figure 1.

Figure 3 is a diagram showing the relation between movement of the operating lever of the

2

motor and branch line pressure, with different motor adjustments.

Figure 4 is a fragmentary view showing means for limiting relative motion of certain parts.

The present pneumatic motor is of the expandable chamber type and includes a flexible diaphragm 10 clamped between a lower rigid member 11 and an upper rigid member 12. Lower member 11, in the nature of a base member, is a metal casting in the form of a shallow cup and includes an upper peripheral flange 13 and a lower attaching stud 14. In addition, a plurality of connection bosses 15 are formed around member 11, each boss including tapped holes 16 for the connecting screws 17 used to secure a connection block 18 in place, and another tapped hole 19 extends through said member for serving as an air connection. Hole 19 is adapted to align with a matching air passage in connection block 18 which also connects with tubing 20. A gasket 21 is normally used between block 18 and boss 15 to prevent leakage and holes 19 not being used are closed by suitable threaded plugs or attached plates. Attaching stud 14 extends through an opening in mounting bracket 22 and is tightened in place by nut 23.

Upper member 12 includes a lower or body portion 26 having a peripheral flange 27 matching flange 13 and further has an upper support or bridging portion 28 extending across the tops of oppositely disposed supporting arms 29 and 30. Supporting arms 29 and 30 are formed with integral ears 31 and 32, respectively, and support member 28 includes a depending centrally located threaded member or portion 33, portions 28 and 33 having a hole 34 extending therethrough, said hole being aligned with the axis of said motor.

Flexible diaphragm 10 is molded in the form of a cup-like member of a heat resisting rubber-like material such as silicone rubber. This dia-

phragm is clamped between flanges 13 and 27 by suitable screws to form a motor chamber between said diaphragm and lower member 11, this chamber being expandable upon a sufficient increase in air pressure in said chamber. Motion of diaphragm 10 is transmitted through a piston-like member 35 having an inclined side wall portion and a flat bottom portion, the side wall portion including extension arms 36 and 37 extending upwardly for connection to a forked operating lever. Forked operating lever 39 includes a slot 40 for connection to the linkage used in operating a unit ventilator, for instance, and also includes spaced fork members 41 and 42 pivoted at 43 and 44 to ears 31 and 32, respectively. Upwardly extending

arms 36 and 37 of piston member 35 are pivotally connected to fork members 41 and 42 by pivots 45 and 46, respectively, so that movement of piston member 35 in a vertical direction causes a rotative movement of lever 39 about pivots 43 and 44.

Piston-like member 35 is held in a lowermost position by a spiral spring 48 bearing against the inner bottom portion of said piston-like member and reacting against an outturned flange 49 of a sheet metal cup-like member 50, member 50 being one of a pair of relatively movable telescoped members used to form a preloaded spring assembly means. The other member of this assembly cooperating with member 50 is a second and shallower inverted cup-like member 51 telescoped inside member 50 and relatively movable therewith member 50 having a plurality of slots 52, only one being shown, (Figures 1 and 4) formed parallel with the axis of movement of said relatively movable members. Member 51 includes outstruck tongue-like stop members 53 extending into slots 52 for limiting the relative outward movement of members 51 and 50 and for preventing rotation of one member with respect to the other. A compression spring 54 extends between the bottom of member 50 and the top of member 51 and urges these members apart, the struck out stop members 53 limiting the motion that can be caused by the spring 54. Spring 54 is, for this illustration, made stiffer than spring 48 so that compression of spring 54 cannot be caused by the mere compression of spring 48. An adjustable mounting for member 51 is formed by a threaded collar 56 securely attached to the central portion of member 51 and threaded on an adjusting bolt 57 extending through hole 34 and having a hexagonal adjusting head 58, bolt 57 being prevented from rising through hole 34 by a snap ring 59 inserted in a suitable groove cut in said member 57, this mounting permitting member 51 to be raised or lowered by rotation of the adjusting head 58, rotation of member 51 being prevented by tongues 53 coacting with grooves 52 in member 50 and member 50 being prevented from rotating, under normal circumstances, by spring 48. A third spring 61, relatively short in length, of sufficient diameter to coat with flange 49 of member 50 is mounted so that its free end is normally spaced above flange 49. The upper end of this spring is snapped into a groove 62 of knurled adjusting nut 63, nut 63 being threaded to travel along threaded portion 33 of support members 28. Nut 63 is ordinarily adjusted so that flange 49 does not engage the lower end of spring 61 until the limiting upper position of lever 39 is being approached, the lever being stopped when the lower ends of slots 52 engage tongues 53. Spring 61 is of such stiffness that the slope of the deflection-pressure curve is abruptly changed when said third spring is engaged, spring 61 thus adding its spring rate to that of spring 54 when said spring 54 is sufficiently deflected. To better show the relation of the various parts of this motor, and the effects of adjusting spring 61 and member 51, the operation of the motor will now be discussed.

Operation

Assuming that tubing 20, in Figure 1, is attached to a suitable controller such as a room thermostat and that slot 40 of lever 39 is connected to a linkage for operating the fresh air dampers of a unit ventilator, let it now be assumed that a slight pressure, such as two pounds per square inch, is imposed on the motor by said

controller, the pressure being exerted through tubing 20, connection block 18, and hole 19 in boss 15 into the motor chamber defined by diaphragm 10 and lower casing member 11. The two pound per square inch pressure tends to lift diaphragm 10 but, because of the force exerted by spring 48, and considering that curve 70 of Figure 3 shows the operating characteristics of the motor as now adjusted, it seems obvious that movement of diaphragm 10 cannot start until almost $2\frac{1}{2}$ pounds per square inch pressure is exerted by the controller. However, as the pressure in the motor chamber is increased by the controller and approaches $2\frac{1}{2}$ pounds per square inch, diaphragm 10 will start moving upwardly, thereby pushing piston member 35 upwardly against spring 48 and rotating operating lever 39 about pivots 43 and 44. This portion of the travel of the motor is identified by line 71 of characteristic curve 70 and, according to this curve, piston 35, operating lever 39, will move about 20% of their full travel before the bottom of piston 35 engages the bottom of cup-like member 50 at 3 pounds per square inch pressure. At this point, due to the preloading of spring 54, the member 50 stops further movement of piston 35 and, with a particular spring 54, the air pressure exerted by the controller, not shown, on the motor may increase until it reaches 8 pounds per square inch without any further movement of the operating lever, this portion of the curve being designated 72 and commonly referred to as the hesitation part of the cycle, this cycle being disclosed in Ewald et al. Patent No. 1,972,766. In ordinary operation, the initial movement of the motor, corresponding to line 71 of the curve, causes a minimum opening of the fresh air dampers such as required by statute for many installations, this minimum opening being assumed to be 20% in the present case. During the hesitation part of the cycle, the fresh air dampers remain fixed at their 20% setting and the further increase in air pressure to the afore-mentioned 8 pounds per square inch causes no damper movement but, in the ordinary installation, this additional air pressure is being used to gradually close the steam valve controlling the heat in the unit ventilator, the system generally being adjusted so that the heat is completely shut off at about the end of the hesitation part of the cycle. Then, if the room temperature continues to rise, and the pressure imposed on the present motor increases, piston 35 and operating arm 39 are moved upwardly again, following portion 73 of curve 70, the deflection characteristics being governed this time by spring 54 which is now being compressed as diaphragm 10 forces piston 35 upwardly, and spring 48 is subject to no further compression because its upper end moves at the same rate as the lower end since cup member 50 is now moving. As shown by portion 73 of curve 70, lever 39 should be driven to its opposite extreme position when the pressure imposed on the motor reaches about 12 pounds per square inch. Obviously, on a reversal in pressure, lever 39 will be operated according to the same characteristics previously discussed, that is the deflection of arm 39 will vary according to the pressure imposed on the motor according to curve 70.

If head 58 of member 57 is now rotated in a manner to raise cup-member 51, and thereby raised member 50 so that an increased deflection of the motor is required before cup member 50 is picked up by piston 35, the pickup point being at about 50% of travel of the motor, curve 74

5

will now be followed. According to this curve, diaphragm 10 is able to start moving piston 35 and lever 39 at about 1½ pounds per square inch pressure because, in raising members 50 and 51, the force exerted by spring 48 is diminished to some extent. With movement started at 1½ pounds per square inch pressure, it appears that the fresh air dampers will be driven to a 50% open position at 3 pounds per square inch and then, on a further increase in pressure to 8 pounds per square inch, no further travel takes place, the initial portion of this curve being similar to 71 of the previous illustration and the hesitation portion corresponding to 72 of curve 70. Then, on the pressure building up sufficiently to collapse spring 54, piston 35 will force member 50 against the compression of spring 54 along the line 75 of curve 74. However, if spring 54 is relied on to resist movement until arm 39 is driven to its upper extreme, then this extreme will be reached at a pressure of about 10 pounds per square inch, thereby shortening the throttling range of other devices which may be used with this apparatus. To avoid this shortening of the throttling range and to insure that arm 39 will be driven to its upper extreme only when the branch line pressure imposed on the motor reaches a predetermined value, such as 12 pounds per square inch, spring 61 is adjusted by rotating nut 63 so that, at some portion of the travel of piston 35 and arm 39, the outwardly turned flange 49 of member 50 engages spring 61 so that further movement of member 50 upwardly will be against the combined resistances of springs 54 and 61, the deflection characteristics now following line 76 of curve 74 and terminating in the 100% travel of the motor corresponding to a 12 pound per square inch branch line pressure.

If member 51 be adjusted to a still higher position, by rotating bolt 57 by head 58, so that the bottom of member 50 is not engaged by piston 35 until about 70% of the travel has taken place, it appears, according to curve 78, that movement will start at about 1 pound per square inch and the hesitation portion of the cycle will be reached at 3 pounds pressure, as before. Upon completion of the hesitation part of the cycle, and as the branch line pressure rises above 8 pounds per square inch, arm 39 again starts moving and will, if its motion is not modified, reach an extreme position at about 9 pounds per square inch pressure. To prevent this, spring 61 is adjusted to be picked up at a somewhat lower position by flange 49 of cup 50. This is necessary because, as previously described, the latter part of the travel of piston 35 and arm 39 is against combined springs 54 and 61 and, due to the present high setting of member 51, spring 54 will not be compressed as much as in the previous example, hence it is necessary that spring 61 be compressed more than before if the proper end position is to be reached at the desired pressure. Then, due to spring 61 being engaged, and with the last portion of travel being against the combined effects of springs 54 and 61, line 79 of curve 78, in alignment with line 76, shows these characteristics and the end position of lever 39 is again reached at the desired 12 pounds per square inch pressure.

Obviously, by a still higher adjustment of members 50 and 51, the hesitation part of the cycle may be displaced upwardly far enough to be ineffective so that 100% movement of lever 39 may be had in direct relation to increase in branch pressure. In this case the limiting

6

position will be reached far below the aforementioned branch pressure but this latter arrangement is particularly desired for a sequence wherein the dampers are gradually opened wide and then the steam valve is gradually closed on a further rise in branch line pressure.

From the above description, it is seen that the present motor is useful for two of the most important unit ventilator cycles and it is adjustable to permit "hesitation" at any desired portion of motor stroke and still finish the cycle at a specified branch line pressure. With the present motor, the hesitation part of the cycle will always start at the same value of air pressure, the value depending upon spring 48, for this spring must be collapsed to its minimum length by engagement of piston 35 with cup 50 to start the "hesitation." Likewise, the end of the hesitation part of the cycle normally depends upon the pressure required to overcome the pre-loading of spring 54, hence the hesitation part of the cycle, for any particular motor, is uniform for all normal adjustments.

An inspection of the present disclosure will reveal many substitutions and equivalents, hence the scope of this invention should be determined only by the appended claims.

I claim:

1. A pneumatic motor comprising a lower rigid member, an upper rigid member, a flexible diaphragm clamped between said members and forming an expansible chamber with one of said rigid members, an operating lever attached to the other of said rigid members, means including said piston-like member operatively connecting said diaphragm to said lever, a preloaded spring means arranged to oppose movement of said diaphragm, said spring means including a pair of relatively movable members, a compression spring arranged between said relatively movable members for urging them apart axially, stop means for limiting their relative axial motion, means for adjustably attaching one of said relatively movable members to said other rigid member so that the other of said relatively movable members is normally spaced above the lowermost position of the piston-like member but may be caused to move by a predetermined movement of said diaphragm, another spring means arranged between the other of said relatively movable members and said piston-like member serving to bias said piston-like member toward its lowermost position, and an additional spring means arranged to be engaged by said other relatively movable member after a predetermined movement of said member, said additional spring means being attached to said other rigid member.

2. A pneumatic motor including a movable flexible diaphragm; an operating member movable by said diaphragm; and a preloaded spring means for opposing movement of said diaphragm beyond a predetermined amount, said spring means including a pair of axially movable members, one of said members having a cup-like form, stop means attached to said axially movable member for limiting the relative axial movement of said axially movable members in a separating direction, one of said members being movable by said diaphragm, and a spring compressed between said members and arranged to bias said members apart within the limits of said stop means.

3. A pneumatic motor including a movable flexible diaphragm; an operating member movable by said diaphragm; a preloaded spring means for

opposing movement of said diaphragm, said spring means including a pair of relatively movable members, one of said members having a diaphragm engaging portion, stop means for limiting the relative separating movement of said members, said one member being movable by said diaphragm, and a spring compressed between said members and arranged to bias said members apart; and adjustment means for said preloaded spring means comprising threaded means for shifting said preloaded spring means toward or away from said diaphragm.

4. A pneumatic motor including a movable, flexible diaphragm; an operating member movable by said diaphragm; a preloaded spring means for opposing movement of said diaphragm, said spring means including a pair of axially movably related members, one of said members having a lower diaphragm engaging portion and an upper flange portion, means for limiting the relative movement of said members in a separating direction, said one member being movable by said diaphragm, and a spring compressed between said members and arranged to bias said members apart; adjustment means for said preloaded spring means comprising threaded means for shifting said preloaded spring means toward or away from said diaphragm; and additional spring means engageable by the upper flange portion of said one member after said member has moved a predetermined distance.

5. A pneumatic motor including a movable, flexible diaphragm; an operating member movable by said diaphragm; a preloaded spring means for opposing movement of said diaphragm, said spring means including a pair of movably related members, means for limiting the relative axial movement of said members, one of said members being movable by said diaphragm, and a spring compressed between said members and arranged to bias said members apart; adjustment means for said preloaded spring means comprising threaded means for shifting said preloaded spring means toward or away from said diaphragm; additional spring means engageable by said one member movable by said diaphragm only after said member has moved a predetermined distance; and means for positioning said additional spring means comprising threaded means axially aligned with said first named threaded means.

6. A pneumatic motor of the expansible chamber type having a movable force exerting piston-like member, first means for opposing movement of said member, second means for opposing movement of said member, said second means being adjustable in a manner to oppose said movement only after a predetermined movement of said member has taken place, movement against said second means being considered a second movement, and third resilient means for opposing movement of said member, said third means being engageable after a predetermined second movement of said member and causing a resistance to movement by a force which increases at a greater rate upon movement on said piston member than does either the first or second means.

7. A pneumatic motor of the expansible chamber type having a movable force exerting piston-like member, first spring means for opposing movement of said member, second spring means concentric with said first spring means for opposing movement of said member, said second spring means being adjustable in a manner to oppose said movement only after a predetermined movement of said member has taken place, and third

5 spring means concentric with said first and second spring means for opposing a predetermined additional movement of said member, said third spring means cooperating with said second spring means to cause an increase in the resistance to movement of said member at a greater rate than caused by either the first or second spring means.

8. A pneumatic motor having an expansible chamber comprising a flexible diaphragm and a rigid member enclosing one side of said diaphragm, a support member attached to said rigid member, a piston-like member arranged to be moved by said diaphragm, said piston-like member having a pair of upstanding arms, pivot means attached to said support member, a forked operating lever pivotally mounted by said pivot means, means pivotally connecting said arms to said forked lever for rotating said lever about said pivot means, a pair of slidably related members, spring means for urging said members apart, stop means for limiting the relative separating movement of said members, one of said members being engageable by said piston-like member, adjusting means for positioning said members to space said one member a predetermined distance from said piston-like member when said piston member is in its lowermost position, and an additional spring arranged to oppose movement of said piston-like member only after it has moved 20 a predetermined distance, said additional spring having sufficient stiffness to require an increase in pressure in said chamber to move said piston-like member against said additional spring means.

9. A pneumatic motor having an expansible chamber comprising a movable flexible diaphragm, a piston-like member arranged to be moved by said diaphragm, an operating lever attached to said piston-like member, a first spring arranged to oppose movement of said piston-like member by said diaphragm, a reaction member for said spring, a second spring, a reaction member for said second spring, said reaction members being axially movably related, said second spring being arranged in compression between said reaction members, stop means for limiting the relative axial movement between said reaction members in a separating direction, said first reaction member including a piston-like member engaging portion, and means for adjusting said second named reaction member to thereby adjust said first spring and the spacing of said piston-like member engaging portion of the first named reaction member and said piston member.

10. A pneumatic motor comprising an expansible chamber, a first spring arranged to resist expansion of said chamber, a preloaded second spring also arranged to resist expansion of said chamber and of such stiffness and preloading that a predetermined increase in the pressure of the air supplied to the motor must take place before there is any deflection of the second spring, a third spring arranged to resist expansion of said chamber after a predetermined expansion has taken place and of sufficient stiffness to insure that the air pressure supplied to said motor must rise to a predetermined value to expand said chamber a predetermined total amount, and means for adjustably positioning said third spring to thereby determine the expansion required of said chamber before said third spring becomes effective.

11. A pneumatic motor having a frame and including an expansible chamber, a first spring arranged to resist expansion of said chamber, a second pair of axially movable members, a second spring

between said members for urging said members apart, said second spring being stiffer than said first spring, stop means coacting with said members for limiting the relative axial motion of said members in a separating direction, one of said members engaging said first spring, and threaded adjusting means coacting with the other of said members for positioning said pair of members, said one member being arranged to resist expansion of said chamber.

12. A pneumatic motor having a frame and including an expansible chamber, a first spring arranged to resist expansion of said chamber, a pair of axially slidably related members urged apart by a second spring, said second spring being stiffer than said first spring, stop means cooperating with said members for limiting the relative motion of said members in a separating direction, one of said members engaging said first spring, threaded adjusting means coacting with the other of said members for positioning said pair of members, the one of said members being arranged to resist expansion of said chamber, and a third spring arranged to be engaged by said one member upon a predetermined expansion of said chamber.

13. A pneumatic motor comprising an expansible chamber formed by a rigid member and a flexible diaphragm, operating means movable by said flexible diaphragm, spring means for opposing movement of said diaphragm, means for mounting said motor comprising a stud member extending from said rigid member and arranged to coact with a suitable bracket, a plurality of air connection bosses disposed around the periphery of said rigid member and approximately equi-

distant from said stud member, air passages through each of said bosses to said chamber, an air connection means attached to one of said connection bosses in registry with its air passage, and sealing means for closing the openings in the connection bosses not being used.

14. A pneumatic motor having a compressed air connection and comprising a movable piston means and an operating member operable thereby, a first spring arranged to oppose an initial movement of said piston means, a second and preloaded spring means arranged to oppose movement of said piston means beyond said initial movement, mechanical means for adjusting the position of said second spring means, and an adjustable third spring arranged to resist movement of said piston means subsequent to deflection of said preloaded spring means, said motor being operable on a cycle wherein hesitation starts at an air pressure depending upon the rate of said first spring and its deflection at the end of said initial movement and ends at an air pressure determined by the force required to overcome said preloaded spring means.
